Primary Examiner — T. Chase Nelson*Assistant Examiner* — Mark Cavanna(74) *Attorney, Agent, or Firm* — Brinks Gilson & Lione(57) **CLAIM**

I claim the ornamental design for a storage case for sample plate, as shown and described.

DESCRIPTION

FIG. 1 is a top perspective view of a storage case for sample plate of the present invention;

FIG. 2 is a front view thereof;

FIG. 3 is a rear view thereof;

FIG. 4 is a top view thereof;

FIG. 5 is a bottom view thereof;

FIG. 6 is a first side view thereof, the second side view being a mirror image thereof; and,

FIG. 7 is a cross-section view taken along the line 7 of FIG. 6.
